UNITED STATES PATENT OFFICE

96,364

DESIGN FOR A SUGAR DISPENSER

Alfonso E. Aviles, Nogales, Ariz., assignor of one-third to Fortunato Mexia, Nogales, Ariz.

Application November 5, 1934, Serial No. 53,887

Term of patent 3½ years

To all whom it may concern:

Be it known that Alfonso E. Aviles, a citizen of the United States of Mexico, residing at Nogales, in the county of Santa Cruz and State of Arizona, has invented a new, original, and ornamental Design for a Sugar Dispenser, of which the following is a specification, reference being had to the accompanying drawing, forming part thereof.

Figure 1 is a top plan view;

Figure 2 is a side elevational view; and
Figure 3 is a perspective view of the article, showing my design.

I claim:

The ornamental design for a sugar dispenser, as shown.

In testimony whereof I affix my signature.

ALFONSO E. AVILES.
